UNITED STATES PATENT OFFICE.

STEPHEN HENRY BLOOMER, OF SEATTLE, WASHINGTON.

GRADING AND EXCAVATING MACHINE.

No. 887,459.

Specification of Letters Patent.

Patented May 12, 1908.

Application filed June 11, 1907. Serial No. 378,448.

To all whom it may concern:

Be it known that I, STEPHEN H. BLOOMER, residing at Seattle, in the county of King and State of Washington, have invented certain new and useful Improvements in Grading and Excavating Machines, of which the following is a specification.

My invention relates to certain new and useful improvements in grading and excavating apparatus, and more particularly has for its object to provide an improved apparatus of this character for moving earth, gravel, etc., from place to place, for leveling surfaces, filling flats, grading and ditching and the like, and which apparatus will be of a simple and economical construction and which will readily and effectively serve its intended purposes.

My present invention, in its more subordinate nature involves certain improvements on the type of grading and excavating machine disclosed in my Patent #776,990, of December 6, 1904, and particularly has for its object to improve the construction of the cable driving mechanism, the corner cable supports and to provide means for supporting the cables between the corner supports so as to enable the cable to be raised or lowered or laterally adjusted as conditions may require.

With other objects in view which will be hereinafter fully described, the invention also embodies certain novel details of construction, combination and arrangement of parts all of which will be first described in detail, and then be specifically pointed out in the appended claims, reference being had to the accompanying drawings, in which:—

Figure 1, is a top plan diagrammatic view of my apparatus. Fig. 2, is a perspective view of the corner cable supporting means. Fig. 2^a, is a detail modified form of bearing suspension. Fig. 3, is a cross section on the line 3—3 of Fig. 1. Fig. 4, is a perspective view on an enlarged scale of the intermediate cable supporting devices. Fig. 5, is an inverted plan view of the sheave shown in Fig. 4. Fig. 6, is a cross section on the line 6—6 of Fig. 5. Fig. 7, is a side elevation of the cable driving mechanism. Fig. 8, is a top plan view thereof. Fig. 9, is a front elevation thereof. Fig. 10, is a rear elevation thereof. Fig. 11, is an enlarged detail perspective view of a portion of the cable driving mechanism, showing the arrangement of the cable guides. Fig. 12, is a detail view of

one of the cable guides showing the manner of adjusting same. Fig. 13, is a detail view of another cable guide showing anti-friction rollers for operating in the main sheave. Fig. 14, is a detail perspective view of one of the scraper securing hooks. Fig. 15, is a detail perspective view of one of the guy rope and controlling sleds. Fig. 16, is a detail perspective view of the inclined approach to the cable driving mechanism. Fig. 17, is a similar view showing the same parts adjusted in another position. Fig. 18, is a perspective view of the dumping mechanism, showing its cable supporting devices.

Referring now to the accompanying drawings in which like letters and numerals of reference indicate like parts in all of the figures, 1 designates the cable driving mechanism that imparts motion to the main cable 20 that passes around corner supports 30 and is adjustably supported between the corner supports 30 by transverse supporting cable and sheave mechanisms 40, as shown.

51 designates scrapers connected to the cable 20 by supplemental secondary cables 50—50, as shown. A dumping mechanism 60 similar to that shown in my patent hereinbefore referred to, is also provided.

Referring now more particularly to Figs. 7 and 8, it will be seen the cable driving mechanism comprises a platform or truck 1^a composed of I-beams mounted on wheels 2 that are fixedly secured to the front axles 3 and run loose on the rear axle 4, the rear axle 4 being connected with the truck 1 by a turn table or fifth-wheel mechanism 5, which is controlled through gears 5^a—6^a and a hand wheel 6^b on a controlling shaft 6 so that by turning the hand wheel, the direction of movement of the truck 1 may be controlled. 7 designates a cross beam that is supported as at 8. 9 designates a main sheave shaft or spindle that is mounted in bearings 9^a in the main frame of the truck and which carries a pair of spaced sheaves 9^b and 9^c respectively that are flat on top and have conical webs 9^d beneath the sheaves being provided with deep peripheral grooves 9^e and having their lower peripheral edges provided with spaced notches 9^f for a purpose hereinafter explained. The beam 7 is braced through turn buckle and rod connections 10, as shown. In the forward end of the truck the driving and power mechanism 70 hereinafter again referred to is mounted. Mounted in bearings 11 on the main frame of the machine is a

second spindle 12 which is held at an angle to the horizontal while the spindle 9 is held vertically. The spindle 12 carries a sheave 12^a of similar form to the sheaves 9^b and 9^c and is also provided with notches 9^f, as shown. The endless cable 20 passes around the sheaves 9^b, 12^a and 9^c, as shown.

13 designates a winding platform supported between the sheaves for the scrapers to pass upon in a manner similar to that shown in my patent hereinbefore referred to. Each end of the inclined plane or platform 13 is provided with a pivoted bolt aperture 13^a and an elongated slot 13^b to coöperate with the extension piece 14^a of the inclined plates 14, which form the approaching ways and leaving ways toward and from the guideway 13. The member 14^a is pivoted at 15 and secured by a bolt 15^a which passes through apertures 14^b in the member 14^a and through the elongated slot 13^b whereby the inclined plate 14 can be arranged at any angle to the guideway 13, as desired. The plate 14 is hingedly secured to the extension member 14^a, as at 14^x, as shown.

In order to enable the small or supplemental cables 50 to wind with the main cable 20, in the grooves of the sheaves 9^b, 12^b, 9^c, I provide guides 16, 17 and 18, the guides 17 and 18 being secured to the free ends of a cross bar 18^a that in turn is secured and carried by the beam 7 of the supporting frame, friction rollers 18^b being provided near the ends of the frame 18^a to enter the grooves of the sheaves 9^c and 12^b, as indicated, so as to form not only guides for the arms, but also supports for the blocks thereof. The guide 18, it will be noticed, is of substantially U-shape in cross section, and at its outer end terminates in a lip 18^c, for a purpose presently to be explained.

The guide 16 is of similar form to the guide 18, except that it is secured by bolts 16^a to a bridge member 117 that has apertures 17^a to coöperate with the bolts 16^a, whereby the guide 16 can be adjusted along the bridge member 117 to the desired position to allow for the main cable entering the groove of the sheave 9^b at different points. The bridge member 117 is secured at 17^b to the underside of the winding platform or guideway 13, as clearly shown in Fig. 12, and the guide 16 is also provided with a lip 16^c, similar to the lip 18^c of the guide 18, and lip 17^c of the guide 17.

By providing guides 16, 17 and 18 and the peripheral slots in the sheaves, the small cables 50 will be wound in the grooves of the sheaves until the scrapers 51 are close up to the sheaves when the small cable 50 will slip over the lips and fall into one of the peripheral notches 9^f of the sheaves and thus the scrapers will be carried around the axis of the shaft in a path of a radius substantially the same as that of the sheave, and thus prevent

the scrapers becoming tangled up as they pass through the driving mechanism.

19 designates a main drive shaft which carries a shiftable pinion 19^a, that meshes with a gear 19^b on the spindle 9 and at the other end the shaft 19 carries a pinion 19^m that meshes with a gear 19^e on a counter-shaft 19^d which is driven through the medium of gears 71^e and 19^f from the main crank shaft 19^g of the engine 70.

71 designates a supporting frame having bearings in which a drum shaft 71^a is journaled, and the drum shaft 71^a carries a drum 71^b which rotates loosely thereon, but may be held to turn with the shaft 71^a by a friction clutch 71^c shiftable into and out of engagement with the drum in any approved manner. Drum shaft 71^a carries a gear wheel 71^d which meshes with the shiftable pinion 71^e on the crank shaft 19^g, any suitable means being provided for shifting the pinion 71^e into and out of engagement with the gear 71^d, such for instance as the ordinary lever 71^f, as shown.

72 designates a pinion on the stub shaft 71^k which meshes with a gear 73 on the front axle 3 of the truck so that the truck may be moved by means of its own power and when the truck is to be moved over bad roads, the friction clutch is shifted to bring the truck 90 1^a into locked engagement with the drum shaft and a cable or anchor to pass around the drum and wind up thereon to aid in drawing the mechanism over roads in a manner similar to that disclosed in my 100 patent hereinbefore referred to.

The engine 70^a is fed from a boiler 70 and any suitable controlling valve mechanism (not shown) may be provided for controlling the operation of the engine 70^a, since the 105 construction of engine and boiler, *per se*, form no part of my present invention.

By reference now more particularly to Fig. 2 it will be noticed that the corner supporting mechanism comprises a base or 110 platform 30^a mounted on caster wheels 30^b and supporting a post 30^c which is suitably braced as at 30^d—30^e.

To the post 30^c the corner sheave 30^f is mounted, the sheave 30^f having its spindle 115 30^g mounted in a bearing 31^a of a bracket 31 which is pivotally secured by an eye bolt 32 to the post 30^c.

31^b designates an eye carried by the bracket 31 to which a block 33 is secured, a 120 second block being secured to the eye bolt 35 on the upper end of the post 30^c and a cable 34^a passes over the blocks 33—34 so that the bracket 31 can be adjustably held in position. The sheave 30^f is grooved to 125 receive the main cable 20 which passes around the same.

36 designates a winding drum which is carried by the corner supporting means and on which a guy cable 36^a is adapted to be 130

wound, the cable 36^a passes through a sheave 36^b on the platform 30^a and through a block 37 anchored to the ground at a definite point and through a second block 38 secured to the supporting post 30^c by a hook and eye bolt 38^a, as shown. A second winding drum 36^x coöperates with a second cable 36^y and sheave 36^z and blocks 38^x and 38^y are similarly secured by anchors to the ground and by eye bolts to the post 30^c, the first guy cables 36^a being held to exert tension at right angles to the second set, as shown. The bracket 31 may be adjustably held by rods and turn buckles 75, as shown, 15 in detail in Fig. 2^a, in place of the blocks 33—34 and the cable which passes thereover. By reference to Figs. 1 and 3, it will be seen that in order to support the main cables 20 at definite heights from the ground between the corner supports and also to enable the cables to be shifted from side to side as shown in dotted lines in Fig. 1, I mount a pair of tripods at each side of the main portion of the apparatus, as shown, and these 25 tripods are designated by the reference numerals 40^a—40^b. The tripod 40^a is anchored to a post or "deadman" and carries a sheave 40^x around which the endless cable 41 passes. The endless cable 41 passes over 30 a double sheave 40^y on the other tripod 40^b and winds around the gypsy drum, whereby the endless cable 41 may be shifted to a greater or less degree as may be found desirable. The sled 42 carries a winch or 35 winding drum 42^a around which an anchor cable 42^b is adapted to be wound, the other ends of the anchor cable 42^b being anchored to a post or "deadman" in the ground, as shown. 40 43 designates a three sheave block which is held over the main cable 20 by means of a double tackle 44 provided with a hook 44^a to hook into an eye bolt 43^a of the sheave 43 and a swivel member 44^b to permit passage of 45 the endless cable 41, which serves to support the sheave block 43. The sheave block 43 is made of boiler iron bent unto substantial U-shape in cross section, the upper and lower portions 43^b and 43^c being spaced apart by 50 collars 43^d and bolts 43^e as shown. Beneath the lower plate 43^c the grooved sheaves 43^f are mounted and the sheaves 43^f are close enough together to prevent the main cable 20 slipping out but spaced sufficiently apart 55 to permit passage of the supplemental or secondary cables which are secured to the scrapers. 45 designates links secured to the block 43 to which the cable 41 is secured so that as the 60 cable 41 is shifted back and forth the blocks 43 will be moved correspondingly to shift the direction of travel of the main cable 20 as shown in dotted lines in Fig. 1. Any number of the supporting mechanisms 40 may be provided as found necessary or desirable. A

block 43 is also supported by a double tackle 44 from a cross beam 60^a of the dumping mechanism 60 so as to support the main cable 20 at this point.

In Fig. 14, I have shown a detailed perspective view of a hook which is carried by the small or supplemental cables 50 and is adapted to hook into the bail 51^x of the scrapers 51 and the hook is designated by the reference numeral 52 and includes a groove 52^a and a circular portion 52^b in which the supplemental cable 50 is held. This portion 52^b is adapted to ride in the grooves of the sheaves as the small cables pass there around and these aid in holding the small cables in the grooves in the sheaves, and in order to minimize wear in the small grooves they may be provided with a series of metallic washers 13, as shown in Fig. 14.

So far as described, the manner in which my invention operates will be best described as follows: The course of ground to be operated upon is first determined by a suitable survey or otherwise and the cable driving mechanism moved into a position at the most suitable point. The corner supports are then placed in proper position and securely anchored, after which the cable 20 is strung and the plows or scrapers attached to the cable. The supplemental cables 50 and transverse supporting mechanism 40 are also placed in position and the cables pass through the sheaves thereof. Should the cable not lie directly over the course to be operated upon, the same may be moved to the desired point by the transverse cable and adjusting and supporting mechanism 40, as before described. The drive mechanism is generally placed at the point where the earth is to be removed. The scraper dumping mechanism 60 is placed at the point where the earth is to be deposited. Upon the cable drive mechanism being set in motion the scrapers are moved forward by the cable and are filled with earth, dirt or gravel. They are then carried forward to the dumping mechanism, which, operating in the manner before described, in my patent hereinbefore referred to, will cause one of the scrapers to dump their load at the place desired. In dumping the scrapers are upset and may be righted by a suitable attendant before they can reach the driving mechanism. After the scrapers have been dumped they pass on forward and are carried around the end support sand back to the driving mechanism. As they arrive at the drive mechanism they will pass up the inclined entrance to the platform and be carried around the spindles in the drive mechanism and pass upwardly down the next incline, where they will be again carried to the place where they again become filled with earth.

From the foregoing description, taken in connection with the accompanying drawings, it is thought the complete construction,

operation and numerous advantages of my invention will be readily understood by those skilled in the art to which the invention appertains.

5. What I claim is:—

1. An apparatus of the character described comprising in combination with an endless cable, a drive mechanism therefor, corner supports including sheaves around which said cable passes, scrapers joined with said cable and movable therewith and adapted to be carried around said drive mechanism and corner supporting sheaves, and transverse endless supporting mechanism for supporting 15 the cable between the corner supports, substantially as shown and described.
2. An apparatus of the character described comprising in combination with an endless cable, a drive mechanism therefor, corner supports including sheaves around which said cable passes, scrapers joined with said cable and movable therewith and adapted to be carried around said drive mechanism and said corner supporting sheaves, transverse 25 endless supporting mechanism for supporting the cable between the corner supports, and means coöperating with said transverse cable supporting mechanism for shifting the first endless cable laterally, substantially as 30 shown and described.
3. An apparatus of the character described comprising in combination with an endless cable, a drive mechanism therefor, said drive mechanism including rotatable sheaves 35 around which the cable takes, scrapers joined with said cable and movable therewith and adapted to be carried around said drive mechanism sheaves, and guides coöperating with said drive mechanism sheaves, substantially 40 as shown and described.
4. An apparatus of the character stated comprising an endless cable, a drive mechanism therefor, said drive mechanism including rotatable sheaves around which the endless 45 cable takes, scrapers, supplemental cables joining the scrapers with the endless cable, and means coöperating with the sheaves of the drive mechanism for guiding the supplemental cables and the sheaves as they pass 50 therearound, substantially as shown and described.
5. An apparatus of the character stated, comprising an endless cable, a drive mechanism therefor, said drive mechanism including rotatable sheaves around which the endless 55 cable takes, scrapers, supplemental cables joining the scrapers with the endless cable, means coöperating with the sheaves of the drive mechanism for guiding the supplemental cables and the sheaves as they pass 60 therearound, and means forming a part of the sheaves for engaging the supplemental cables at times, substantially as shown and described.
6. An apparatus of the character stated,

comprising in combination with an endless cable, a drive mechanism therefor, scrapers joined with said cable, said drive mechanism including rotatable sheaves, means coöperating with the drive mechanism for guiding the scrapers around the sheaves, supplemental cables connecting said scrapers with the endless cable, and means coöperating with the sheaves for guiding the supplemental cables into the sheaves, substantially as shown and 75 described.

7. An apparatus of the character stated, comprising in combination with an endless cable, a drive mechanism therefor, scrapers joined with said cable, said drive mechanism including rotatable sheaves, means coöperating with the drive mechanism for guiding the scrapers around the sheaves, supplemental cables connecting said scrapers with the endless cable, means coöperating with the sheaves for guiding the supplemental cable into the sheaves, said sheaves having notched peripheral portions for receiving the supplemental cables, at times, substantially as shown and described.

8. An apparatus of the character stated, comprising in combination with an endless conveyer cable, conveyers, supplemental cables connecting the conveyers with the endless cable, means for imparting unidirectional movement to said cable, said means including a drive mechanism having a plurality of rotatable sheaves around which the cable passes, and a winding platform for directing the scrapers in their movement around the sheaves, and guides coöperating with the sheaves for directing the supplemental cables into the sheaves, substantially as shown and described.

9. An apparatus of the character stated, comprising in combination with an endless conveyer cable, conveyers, supplemental cables connecting the conveyers with the endless cable, means for imparting unidirectional movement to said cable, said means including a drive mechanism having a plurality of rotatable sheaves around which the cable passes, a winding platform for directing the scrapers in their movement around the sheaves, guides coöperating with the sheaves for directing the supplemental cables into the sheaves, and adjustable entrance and leaving inclined ways coöperating with said winding platform, substantially as shown and described.

10. In an apparatus of the class described, a drive mechanism comprising in combination with a wheeled truck, a pair of spindles mounted thereon, sheaves secured to said spindles, a winding platform mounted on the wheeled truck, means for imparting motion to said spindles, and means for imparting motion to the wheeled truck at times.

11. In an apparatus of the class described, a drive mechanism comprising in combina-

tion with a wheeled truck, a pair of spindles mounted thereon, sheaves secured to said spindles, a winding platform mounted on the wheeled truck, means for imparting motion 5 to said spindles, means for imparting motion to the wheeled truck at times, and cable guides coöperating with said sheaves, substantially as shown and described.

12. In an apparatus of the class described, 10 a drive mechanism comprising in combination with a wheeled truck, a pair of spindles mounted thereon, sheaves secured to said spindles, a winding platform mounted on the wheeled truck, means for imparting motion 15 to said spindles, means for imparting motion to the wheeled truck at times, said sheaves having notched peripheral portions, substantially as shown and described.

13. In an apparatus of the class described, 20 a drive mechanism comprising in combination with a wheeled truck, a pair of spindles mounted thereon, sheaves secured to said spindles, a winding platform mounted on the wheeled truck, means for imparting motion 25 to said spindles, means for imparting motion to the wheeled truck at times, said sheaves having notched peripheral portions, and cable guides for said sheaves, substantially as shown and for the purposes described.

30 14. In an apparatus of the character described, a drive mechanism comprising in combination with a wheeled truck, spindles mounted thereon, sheaves secured to said spindles, a winding platform mounted on the truck between the sheaves, a drive motor for imparting movement to the spindles, a drum mounted on the truck, operated by said drive motor, and means for imparting motion to the truck from said drive motor.

40 15. An excavating apparatus comprising in combination with a continuously moving conveyer cable, means for excavating and carrying dirt from one place and moving same parallel with the conveyer cable to a predetermined point, means for automatically depositing said dirt at said point on one side or the other, means for supporting the cable at said depositing point.

16. An excavating apparatus comprising 50 in combination with a continuously moving conveyer cable, means for excavating and carrying dirt from one place and moving same parallel with the conveyer cable to a predetermined point, means for automatically depositing said dirt at said point on one side or the other, means for supporting the cable at said depositing point, and means for supporting and laterally adjusting the cable, at predetermined places, substantially as 55 shown and described.

17. An excavating machine comprising 60 in combination with a main cable, excavators, supplemental cables connecting the excavators with the main cable, a drive mechanism for the main cable, means coöp-

erating with the excavators for depositing the dirt at a predetermined point, corner supporting means for said main cable, said corner supporting means including adjustably held cable sheaves, substantially as shown 70 and described.

18. An excavating machine comprising in combination with a main cable, excavators, supplemental cables connecting the excavators with the main cable, a drive 75 mechanism for the main cable, means coöperating with the excavators for depositing the dirt at a predetermined point, corner supporting means for said main cable, said corner supporting means including adjustably held cable sheaves, and transverse endless 80 cables held over the main cable and means for supporting the main cable from said transverse endless cables.

19. An excavating machine comprising 85 in combination with a main cable, excavators, supplemental cables connecting the excavators with the main cable, a drive mechanism for the main cable, means coöperating with the excavators for depositing 90 the dirt at a predetermined point, corner supporting means for said cable, said corner supporting means including adjustably held cable sheaves, and transverse endless cables held over the main cable and means for adjustably supporting the main cable from 95 said transverse endless cables, substantially as shown and described.

20. An excavating machine comprising 100 in combination with a main cable, excavators, supplemental cables connecting the excavators with the main cable, a drive mechanism for the main cable, means coöperating with the excavators for depositing the dirt at a predetermined point, corner 105 supporting means for said main cable said corner supporting means including adjustably held cable sheaves, transverse endless cables held over the main cable, means for adjustably supporting the main cable from said transverse endless cables, said last named 110 means comprising a sheave block for engaging the main cable, and block and tackle for supporting the sheave block from the transverse endless cable substantially as shown 115 and described.

21. An excavating machine comprising 120 in combination with a main cable, excavators, supplemental cables connecting the excavators with the main cable, a drive mechanism for the main cable, means coöperating with the excavators for depositing the dirt at a predetermined point, corner supporting means for said main cable, said corner supporting means including adjustably held cable sheaves, transverse endless cables held over the main sheaves, means for adjustably supporting the main cable from said transverse endless cables, said last named 125 means comprising a sheave block for engag- 130

ing the main cable, block and tackle for supporting the sheave block from the transverse endless cable, and means for coöperating with the transverse endless cable for moving 5 the same to shift the main cable laterally, substantially as shown and described.

22. An apparatus of the character stated, comprising the combination with an endless conveyer cable, a drive mechanism therefor, 10 scrapers, supplemental connecting cables for connecting each of the scrapers with the conveyer cable, a hook carried by the supplemental connecting cables for hooking into the scrapers, said hook having a sheave engaging 15 portion, a drive mechanism for said endless conveyer cable, said drive mechanism including rotatable spindles, grooved sheaves mounted thereon, around which the conveyer cable and connecting cables pass, 20 means coöperating with said sheaves for guiding the connecting cable into the grooves thereof, and means for rotating the spindles.

23. An apparatus of the character stated, comprising the combination with an endless conveyer cable, a drive mechanism therefor, 25 scrapers, supplemental connecting cables for connecting each of the scrapers with the conveyer cable, a hook carried by the supplemental connecting cables for hooking into 30 the scrapers, said hook having a sheave engaging portion, a drive mechanism for said endless conveyer cable, said drive mechanism including rotatable spindles, grooved sheaves mounted thereon, around which the 35 conveyer cable and connecting cables pass, means coöperating with said sheaves for guiding the connecting cables into the grooves thereof, means for rotating the spindles, and a winding platform coöperating with said 40 drive mechanism sheaves for guiding the scrapers around the same, substantially as shown and described.

24. In an apparatus of the character stated, comprising the combination with an 45 endless conveyer cable, a drive mechanism therefor, scrapers, supplemental connecting cables for connecting each of the scrapers with the conveyer cable, a hook carried by the supplemental connecting cables for hooking 50 into the scrapers, said hook having a sheave engaging portion, a drive mechanism for said endless conveyer cable, said drive mechanism including rotatable spindles, grooved sheaves mounted thereon, around which the 55 conveyer cable and connecting cables pass,

means coöperating with said sheaves for guiding the connecting cable into the grooves thereof, means for rotating the spindles, a winding platform coöperating with said drive mechanism sheaves for guiding the scrapers 60 around the same, said sheaves having peripheral notched portions, substantially as shown and described.

25. In an apparatus of the class described, a drive mechanism comprising a wheeled 65 truck, a drive motor mounted thereon, means for moving said wheeled truck from said drive motor, a winding drum carried by the truck, means for operating said winding drum from the drive motor, rotatable spindles 70 mounted on the truck, grooved pulleys carried by the spindles, means for rotating the spindles from the drive motor, and a winding platform coöperating with said spindles.

26. In an apparatus of the class described, a drive mechanism comprising a wheeled truck, a drive motor mounted thereon, means for moving said wheeled truck from said drive motor, a winding drum carried by the 80 truck, means for operating said winding drum from the drive motor, rotatable spindles mounted on the truck, grooved pulleys carried by the spindles, means for rotating the spindles from the drive motor, a winding 85 platform coöperating with said spindles, and an adjustable incline secured to the winding platform, substantially as shown and described.

27. In an apparatus of the class described, 90 a drive mechanism comprising a wheeled truck, a drive motor mounted thereon, means for moving said wheeled truck from said drive motor, a winding drum carried by the truck, means for operating said winding 95 drum, from the drive motor, rotatable spindles mounted on the truck, grooved pulleys carried by the spindles, means for rotating the spindles from the drive motor, a winding platform coöperating with said spindles, an 100 adjustable incline secured to the winding platform, said adjustable incline comprising an adjustable plate pivotally and adjustably secured to the winding platform, and an incline plate hingedly secured to the adjustable 105 plate.
